Maurice Raup
ATTORNEY

UNITED STATES PATENT OFFICE.

AUGUST HABENICHT, OF BAILEYVILLE, ILLINOIS.

RAILROAD TIE.

Application filed October 9, 1925. Serial No. 61,408.

This invention relates to improvements in railway track construction with particular reference to new and novel means for securing the rails upon metallic ties in a manner to completely prevent spreading of the rails from side pressure caused by contact between the flanges of car wheels and the rail heads.

Accidents from this cause are of frequent 10 and increasing occurrence due primarily to shifting or decayed ties.

Replacement being frequently postponed because of the consequent cost of chemically treated ties of the wooden variety. Metallic 15 ties of the type shown are well adapted to be coated by galvanic processes or heat treatments that anticipate and largely prevent corrosion between relatively close adjustment of parts.

20 The principal object of this invention is the provision of means whereby rails of conventional type may be rigidly secured to metallic ties adapted to be securely embedded in the roadway.

25 Another object is to provide means whereby rails may be expeditiously aligned and prevented by fixed abutments from side movement.

A further object provides means whereby 30 water or moisture will be conveyed away from the point of contact between the rails and the ties.

And a still further object is the means provided for mechanically clamping the 35 rails to the ties.

These and other objects are accomplished by the novel and practical construction and combination of parts hereinafter described and shown in the accompanying drawing, 40 forming a material part of this invention, and in which:

Figure 1 is a side elevation of a railway tie made in accordance with the invention.

Figure 2 is a top plan view of the same.

45 Figure 3 is a longitudinal sectional view taken on the line 3-3 of Figure 2.

Figure 4 is a longitudinal sectional view taken on line 4-4 of Figure 2.

Figure 5 is an enlarged side view of the 50 clamp member.

Figure 6 is a plan view of the same member.

Referring now in detail to the figures, the numeral 10 designates a pair of track rails,

transversely disposed across a metallic rail tie, comprising a rectangular plate body 11, having gradually widening end elements 12, angularly down-turned and adapted to be securely embedded in the roadbed material. 55

Formed transversely of the body 11 are 60 depressed channel elements 13 spaced apart at predetermined distances, and adapted to receive therein the base elements 14 of the rails 10.

Rectangular raised locking lug elements 65 15 integral with the plate 11 and in line with the outer ledges of the channels 13, are produced by partially cutting through the base plate and forcing the lug upward.

A space 16, shown in Figure 4, provides an 70 opening through which water may pass from the channel to the road bed. A further means for permitting accumulated moisture to pass from between the rail base 14 and the channel 13 is the tubular integral element 17 75 formed through the tie, central with the channel sides, as shown in Figure 3.

A rail clamp, shown in Figure 5, comprises a body 18, a segmental clamp element 19, a screw threaded element 20, and a head 80 21 adapted to receive a wrench for tightening.

Referring to Figure 3 it will be seen that the threaded element 20 of the rail clamp unit, engages suitable threaded openings 85 formed through the tie, and that as the unit is turned by the head 21, the segment clamp 19 will engage the rail base 14 forcing it downward and rigidly securing it 90 within the channel of the tie.

From the foregoing description it will be seen that a practical, efficient railway tie has been disclosed and that it is applicable to any gauge or weight of track and that substitution of the old type of wooden tie 95 for the type described can be readily accomplished.

It will also be seen that objections to metal ties in general has been overcome by providing means for disposing of accumulated moisture between abutting surfaces of the rails and tie elements.

Having thus described and illustrated my invention, what I claim as new and desire to secure by Letters Patent, is:-

1. A railway tie comprising a metallic plate having broadened downturned ends, right-angled rail base receiving channels

formed transversely in the face of said plate, square hooks integral with said plate at the outer edges of said channels, and means in said channels for draining the same.

5 2. A railway tie comprising a metallic plate, the ends of said plates being widened to approximately twice the width of their

main portions and bent angularly downward, with spaced transverse channels having vertical walls and means intermediate said walls for draining the channels.

In witness whereof I have affixed my signature.

AUGUST HABENICHT.
